UNITED STATES PATENT OFFICE.

EDWARD J. FOSTER, OF MOUNT AUBURN, ILLINOIS.

FORM FOR CONSTRUCTING DRAIN AND SEWER TILES.

Application filed September 7, 1926. Serial No. 133,989.

Experience has taught those skilled in this art that the weakness of the present style tile drain is the relatively short length of the tile. When the tile is laid in sandy soil the water in its course through the drain drops through the cracks or joints of the drain and causes the sand to wash out from under the tile and forms a basin under the same; the tile eventually drops into this basin and the drain is ruined. The important object of my invention is to eliminate these defects by making a continuous bottom or one constructed solid with a sectional top.

Another very important object of my invention lies in the provision of moulds which allow the tile sections to be formed while the ditch is being dug whereby the sections may be made as needed and cemented together so as to form practically a one-piece or integral drain structure.

Another very important object of the invention lies in the provision of a form which consists of few parts of very simple construction which may be easily and quickly assembled and disassembled.

A still further very important object of the invention lies in the provision of moulds which are inexpensive to manufacture, strong and durable, reliable and efficient, and otherwise well adapted for the purpose for which they are designed.

With the above and numerous other objects in view as will appear as the description proceeds, the invention resides in certain novel features of construction, and in the combination and arrangement of parts as will be hereinafter more fully described and claimed.

In the drawing:

Fig. 1 is a bottom plan view of the top form,

Fig. 2 is a top plan view of the bottom form,

Fig. 3 is a section through the top form,

Fig. 4 is a section through the bottom form,

Fig. 5 is a fragmentary elevation of a drain completed with the forms,

Fig. 6 is an end elevation of one section of the drain,

Fig. 7 is a perspective view of one of the rails used with the forms,

Fig. 8 is an elevation of the modification of the rail,

Fig. 9 is an end elevation of said modification, 55

Fig. 10 is an elevation of an end of another embodiment of the mould,

Fig. 11 is another elevation thereof looking at the opposite side, as shown in Fig. 10, 60

Fig. 12 is a perspective view of an end member showing still another embodiment,

Figs. 13, 14 and 15 are elevations of still other embodiments of the end member.

Referring to the drawings in detail it will be seen that the top form illustrated to advantage in Figs. 1 and 3 includes a pair of end members 5 and side rails 6.

The end members 5 are of semi-circular formation being provided on their outer edges with notches 7 for receiving reinforcing rods and

on their ends with notches 8 which are disposed also in the outer edges for the reception of the side rails 6.

In using this top mould the ditch into which the drain is to be disposed is partially dug semi-cylindrical and the form is set therein and the concrete

70 poured in the form to form a semi-cylindrical section indicated at 10 in Figs. 5 and 6 and the side rails 6 will cause the formation

75 of the grooves 11 at the side edges of the section. The sections will be removed from the ditch after the concrete has properly set.

The ditch is then dug the desired depth and the bottom section formed therein by using

80 the moulds shown in Figs. 2 and 4. This bottom mould includes end members 12 and side rails 6.

The end members 12 are provided with the notches 14 similar to notches 7 and notches 15 at their ends and at the inner edges for receiving the rails 6.

When the end members and side rails are assembled the concrete is poured in the form and will

85 produce a section 16, the side rails forming the grooves 17 so that a tongue and groove connection is provided between the side edges of the top and bottom sections.

After the bottom sections are properly set the top sections will be placed thereon as clearly indicated in Fig. 6 and the length may be cemented together as is indicated at 18.

In Figs. 8 and 9 I have shown another embodiment of the side rails. This rail is indicated

90 by the numeral 19 and is of an elongated tubular construction of substantial square cross sections having a ridge 20 extending

95 from one corner longitudinally thereof and co-planar with one face and on said face and

100

105

Fig. 8 is an elevation of the modification of the rail,

ridge there are disposed suitable indicia 21. This embodiment of the side rail is light in construction and enables the drain sections to be made in different lengths as will obviously be desirable.

In Figs. 10 and 11 an embodiment of the end members has been shown denoted by the numeral 22 and having outer edge notches 23 and provided with detachable end plates 24 held in place by bolts 25. These plates are of arcuate formation and their inner edges have projecting therefrom lugs 26 on which the rails 6 or 19 may rest. In Figs. 13 and 14 substantially the same embodiment is shown except that the plates 24 are provided either with notches 27 or projections 28 for forming a tongue and groove connection between the top and bottom sections formed by the bowl. In Fig. 12 an intersection 29 has been illustrated provided with openings 30 through which may be extended reinforcing rods and provided with suitable end notches 31 for receiving end rails 6 or 19. In Fig. 15 an embodiment of the end member indicated at 32 and provided with a rod 34 extending therefrom and projecting beyond the ends to form dowel pins.

It is thought that the construction, utility, and advantages of this invention will now be apparent to those skilled in this art without the necessity of a more detailed description thereof. The present embodiments of the invention have been disclosed in detail merely by way of examples since in actual practice they have attained the features of advantage enumerated as desirable in the statement of the invention and the above description. It will be apparent

that changes in the details of construction 40 may be resorted to without departing from the spirit or scope of the invention as hereinafter claimed or sacrificing any of its advantages.

Having thus described my invention, 45 what I claim as new is:

1. A form of the class described, including a pair of semi-circular end members having notches at their extremities and a pair of side rails restable in said notches.

2. A form of the class described, including a pair of semi-circular end members, a pair of side rails, and means on the extremities of the end members for receiving the side rails.

3. A form of the class described, including a pair of semi-circular end members, a pair of side rails, and means on the extremities of the end members for receiving the side rails, said means including structures for forming tongue and grooves.

4. A form of the class described, including, in combination, a pair of semi-circular end members, a pair of side rails, means for resting the side rails on the end members, said side rails being of a square tubular formation having a ridge along one corner longitudinally thereof co-planar with one face, said one face and ridge being provided with measuring indicia.

5. A form of the class described, including a pair of semi-circular end members, arcuate plates detachably engaged on the ends of the end members and formed with inwardly extending lugs, and a pair of side rails restable on said lugs.

In testimony whereof I affix my signature.

EDWARD J. FOSTER.
